DEVICES FOR HOLDING FILTERS INTENDED TO STOP PARTICLES IN SUSPENSION IN GASEOUS STREAMS

René Pierre Francois Donguy, Vanves, France, assignor to Commissariat à l'Energie Atomique, Paris, France, a state administration of France

Filed Mar. 5, 1958, Ser. No. 719,305

Claims priority, application France Mar. 6, 1957

3 Claims. (Cl. 183—62)

The present invention relates to devices for holding filters intended to stop particles in suspension in gaseous streams, and in particular in gaseous streams under pressure. The invention is more especially concerned with such devices for holding filters intended to stop radioactive particles.

The chief object of the present invention is to provide a device of this kind which is better adapted to meet the requirements of practice, and in particular which permits of easily replacing a used filter by a new one.

According to the present invention, this device includes two tubular sockets adapted to be fixed in gas-tight fashion on the respective ends of two portions of the circuit through which said gaseous stream is flowing, each of said sockets being provided with a central passage forming an extension of the circuit portion on which said socket is fixed, said central passage forming an orifice in the face of said last mentioned socket located opposite the other of said sockets, the respective outer side walls of said two sockets being located in a common cylindrical surface, said two sockets being rigidly assembled together in line with each other through means provided with at least one aperture sufficient to permit passage of a filter therethrough, means operable from a distance being provided on at least one of said sockets for removably fixing a filter on said orifice of one of said sockets so as tightly to apply the periphery of said orifice against the edge of said orifice, a cylindrical sleeve being fitted on the outer side walls of both of said sockets, said sleeve being slidable along said sockets, whereby said sleeve can occupy either a position in which it surrounds both of said sockets or a position in which it surrounds only one of said sockets, and means being provided for sliding from a distance said sleeve with respect to said sockets.

Preferred embodiments of the present invention will be hereinafter described with reference to the accompanying drawing, given merely by way of example and in which:

Fig. 1 is an axial vertical section of a filter holding device according to the invention, said device being shown in working position.

Fig. 2 is an elevational view of the same device with the covering sleeve lowered in order to permit replacement of the filter.

The apparatus shown by the drawing is intended to mount a filter 1 between a portion 2 and a portion 3 of a circuit through which circulates a gas under pressure in which radioactive aerosols are in suspension.

It should first be reminded that, in the filtering of such a gas (which may for instance be the coolant gas of a nuclear reactor, or a gas which had been in contact with liquid effluents and which contains micro-drops in suspension, as it is the case in plants for the extraction of plutonium), the access of the soiled and active filters is a dangerous operation because their removal requires the use of tools the standard dimensions of which are relatively small, which compels the worker to be close

2

to the filter and involves the risk of having him exposed to radiations or to cause him to absorb radioactive aerosols. Furthermore, such an operation is often delicate since the mechanism for opening the filter-holder must be provided so as to ensure a very good fluidtightness, not only to the dust conveyed by the gas but also to the high pressure thereof.

In the embodiment of the present invention illustrated by the drawings, the filter-holder includes two sockets 4 and 5 in the form of cylinders of revolution fixed, for instance by welding, on the ends of the portions 2 and 3 of the gas circulation circuit.

These two sockets 4 and 5 are rigidly assembled together by means of elements 6 provided with apertures 15 and constituted for instance by portions of a jacket in the form of a cylinder of revolution secured on said sockets 4 and 5 by means of screws 7 and provided with wide apertures 8.

Of course, the whole of elements 4, 5 and 6 might be made of a single part provided with suitable apertures.

Filter 1 is mounted on a ring 9 one end of which is screw-threaded so that it can be screwed on a cylindrical projection 10 of socket 5 (which is provided with corresponding screw-threads). The other end of ring 9 is adapted to support the periphery of the filter 1 and to apply it, in a dust-tight fashion, against a flat annular joint 11 mounted in a suitable housing of socket 4.

Ring 9 is advantageously provided with radial holes 12 diametrically opposed.

The side walls of sockets 4 and 5 are provided with annular grooves in which are mounted toroidal-shaped packing members 13 intended to be applied against the inner wall of a sleeve 14 in the form of a cylinder of revolution the inner diameter of which is substantially equal to the outer diameter of sockets 4 and 5, said sleeve 14 being capable of supporting the pressure of the gas to be treated.

The outer wall of sleeve 14 is provided with an annular projection 15 provided with a hole 16 parallel to the axis of said sleeve.

Sleeve 14 is further provided with a longitudinal notch 17 capable of guiding a pin 18 rigid with socket 4. It further includes an abutment 19 to limit its upward movement with respect to socket 5.

Sleeve 14 and socket 4 are provided with respective apertures 20 and 21 adapted to come opposite one another when the sleeve is in position around the two sockets. A key 22 can then be introduced into these holes so as to lock the sleeve in position on the sockets.

If it is supposed that initially the filter-holder is in this working position (Fig. 1), the removal of a filter to be replaced by a fresh one can be effected as follows:

The inflow of gas through conduit 2 is cut off. Key 22 is removed.

The curved ends of two rods 23 are engaged into holes 16 and these rods are pulled in a direction parallel to the axis of sleeve 14, which causes this sleeve to slide with respect to sockets 4 and 5 and to disclose the apertures 8. The use of a grease including some amount of silicon permits of ensuring a good sliding of the sleeve with respect to the sockets even at high temperatures.

A rod 24, of relatively great length, is inserted through one of these apertures 8 into two corresponding radial apertures 12 of ring 9, and this rod is rotated about the axis of the ring so as to screw said ring on projection 10, which releases the filter.

It suffices then to displace this filter to cause it to drop in a suitable vessel.

All these operations can be effected without difficulty and by means of very long rods, whereby the hands of the operator, and the operator himself, are at a distance such

from the filter that the noxious effects thereof are sufficiently attenuated.

The mounting of a new filter is then obtained by effecting the above mentioned operations in the reverse order.

At the end of the upward movement of sleeve 14, notch 17 engages lug 18 so that holes 20 and 21 are in register and permit the introduction of the locking key 22.

It should be noted that the device according to this invention gives a very good gas-tightness. In particular, the pressure of the gas circulating through the device cannot displace sleeve 14 because this pressure exerts a radial effort which is perfectly balanced.

However, the removal of the filter is very easy since the periphery of said filter is not applied in a very strong manner against joint 11, this application being intended to ensure gas-tightness only for the very small difference between the pressures existing on the respective sides of the filter.

The filter may be made of any suitable material such as paper, glass wool or silica wool, sintered material, etc.

By way of example, it is indicated that a filter having a useful area of 9 sq. cm. and a thickness of 4 mm., mounted on a support made according to the invention, was inserted in a gas circulation circuit where the pressure was 18 kg./sq. cm. No leakage was detected.

A particularly interesting application of the invention consists in introducing a filter mounted in such a support in a conduit for collecting the coolant gas from a nuclear reactor, upstream of a counting device, in order to stop the radioactive aerosols which might deteriorate some parts of said counting device.

In a general manner, while I have, in the above description, disclosed what I deem to be practical and efficient embodiments of my invention, it should be well understood that I do not wish to be limited thereto as there might be changes made in the arrangement, disposition and form of the parts without departing from the principle of the present invention as comprehended within the scope of the accompanying claims.

What I claim is:

1. A device for holding a filter intended to stop particles in suspension in a gaseous stream, which device comprises, in combination, two tubular sockets adapted

to be fixed in gas-tight fashion on the respective ends of two portions of the circuit through which said gaseous stream is flowing, each of said sockets being provided with a central passage forming an extension of the circuit portion on which said socket is fixed, said central passage forming an orifice in the face of said last mentioned socket located opposite the other of said sockets, the respective outer side walls of said two sockets being located in a common cylindrical surface, means for rigidly assembling said two sockets together in line with each other, said means being provided with at least one aperture sufficient to permit passage of a filter therethrough in a direction transverse to the common axis of said sockets, means operable from a distance on at least one of said sockets for removably fixing a filter on said orifice of one of said sockets so as tightly to apply the periphery of said filter against the edge of said orifice, a cylindrical sleeve fitting in gas-tight fashion on the outer side walls of both of said sockets and slidable longitudinally therewith, whereby said sleeve can occupy either a position in which it surrounds both of said sockets or a position in which it surrounds only one of said sockets, and means operative from a distance for sliding said sleeve with respect to said sockets.

2. A device according to claim 1 in which the outer side walls of said sockets are provided with grooves, further including toroidal-shaped joints inserted in said grooves and intended to be applied against the inner wall of said sleeve.

3. A device according to claim 1 in which the means for removably fixing the filter include a ring screwed at one end on one of said sockets and adapted at the other end to support the filter and to apply it against the other socket.
